UNITED STATES PATENT OFFICE.

SWEN R. SWENSON, OF SOUTH ORANGE, NEW JERSEY, ASSIGNOR TO MULTIPLE ELECTRIC PRODUCTS COMPANY, INC., OF NEW YORK, N. Y., A CORPORATION OF NEW YORK.

SEPARABLE PLUG.

Application filed February 20, 1922. Serial No. 537,770.

My invention relates to separable attachment plugs for use in those cases where it is desirable to connect electric translating devices, for example, an electric iron, in an electric circuit terminating in a socket, such as a screw socket for an electric lamp bulb having a screw base.

The object of my invention is to compel the operator when connecting or disconnecting the plug and the socket to first separate the member carrying the wires leading to the translating device from the other member of the plug, thus providing increased safety in the making of the connections above referred to and preventing the twisting of the wires between the separable plug and the translating device and obviating the wear and tear on the wires and terminals which heretofore has been caused by the twisting of the wires in the act of screwing connecting plugs into the socket.

I accomplish the object of my invention in one embodiment, by providing the member carrying the flexible lead wires with a revolvable cap or sleeve completely covering the outer face of said member and the sides thereof and extending beyond the sides of the member to be inserted in the socket when the parts of the separable plug are assembled; and in another embodiment by providing the member of the separable plug engaging with the socket with devices cooperating with and actuated by the terminals of the other member and serving to lock, fasten, and bind said socket engaging member in the socket, or to prevent the entry of said member into the socket if the two parts are previously assembled.

By way of example of the application of my invention I have chosen to illustrate it in connection with a socket of the screw type, but it will be understood that the invention is applicable to other types of sockets.

In the accompanying drawings,

Fig. 1 is a vertical section of one form of my new separable plugs assembled and showing the revolvable cap for preventing the insertion or withdrawal of the socket engaging member into or out of the socket while the members of the separable plug are assembled;

Fig. 2 is a bottom view of the member

carrying the wires leading to a translating device;

Fig. 3 is a vertical view, partly sectional, 55 of another form of my new separable plugs showing the socket engaging member provided with suitable locking, fastening, or binding mechanism for preventing its entry into or withdrawal from the socket while the 60 members are assembled;

Fig. 4 is a bottom view of the device of Fig. 3 and along the line 4—4 thereof;

Fig. 5 is a vertical view of the device of Fig. 3 assembled in a screw socket, the socket 65 being cut away to show the relation of the locking, fastening, or binding devices and the socket wall at the place of contact thereof;

Fig. 6 is a view of a guide and supporting member on which the locking, fastening, or 70 binding piece slides into and out of locking position.

In the drawings, 1 is a screw plug engaging with a suitable screw socket (not shown) 75 said plug being provided with contact members 2 and 3 for engaging with the contacts of the socket, and 4 is the removable member of said plug in which is mounted extension terminals 5 and 6 engaging with the contact members 2 and 3 of the plug 1. The terminals 5 and 6 are secured to the member 4 by screws 7 and 8, as shown in Fig. 2, and wires 9 and 10 are connected thereto and pass through a tube 11 and thence to a suitable translating device. A cap piece, 12, is 80 mounted on the outer face of the removable member 4 and held in place thereon by the circular flange of the tube 11, the cap piece being of any suitable material, as iron, hard rubber, etc., as desired, and being free to revolve. As shown in the drawings, the cap piece 12 covers the outer face and sides of the member 4 and as much of the sides of the member 1 as desired to serve the purpose contemplated.

In the utilization of a structure such as that described above, it is apparent that, due to the presence of the freely revolving cap piece 12, an operator wishing to connect the plug into a socket must first separate the 100 member 4 from the member 1, as by a pulling action, whereupon the plug 1 is screwed into the socket and thereafter the member 4 is pushed into the plug 1, completing the

connection. When it is desired to disconnect the separable plug 1-4 from the socket it is apparent that, due to the presence of the revolvable cap-piece 12, the operator must first pull the member 4 out from the plug 1, whereupon the plug 1 is unscrewed from the socket.

In Fig. 3 the object of my invention is accomplished by incorporating suitable mechanism in the socket engaging member of the separable plug. To this end, the socket engaging member 1^a is cut away for a portion of its length as shown at the left in Figs. 3 and 4 to provide room therein for the mounting of the mechanism about to be described. Here the spring contact member is of the hair pin type, as shown at 2^a. The end of one leg of said contact is soldered to the screw shell at 13, the upper portion 20 of said leg bearing against the wall of the channel in the plug, the other leg passing down the channel and the end thereof terminating in a hole in a movable pawl, 14, which rests on a plate, 15, provided with flanges 16, 16 for guiding the pawl 15 in its backward and forward movements, said plate being soldered to the bottom of the screw base and flush therewith.

In assembling the plug 4-1^a, the member 1^a is screwed into a socket, shown in section at 17, Fig. 5, and the member 4 is then pushed into place on the member 1, the extension terminals 5 and 6 of the member 4 contacting with the internal spring contacts 3 and 2^a of the member 1^a, forcing the legs of the spring 2^a together and moving the pawl 14 outward to a position where it is pressed against the wall of the socket 17, as shown in Fig. 5, thus locking the assembled plug into the socket. Should the operator thereafter attempt to remove the assembled plug from the socket by unscrewing it, the pawl 14 will rock up on one leg, due to the construction shown, and jam in the socket at the point of contact therewith. The pulling out of the member 4 from the member 1^a causes the legs of the spring contact 2^a to spread apart and move the pawl out of contact with the socket 17, whereupon the member 1^a can be removed from the socket and reinserted thereinto at will so long as the plug is in the unassembled condition and the deleterious results referred to above are obviated in the making and breaking of electrical connection of the character described.

It is to be understood that the invention is not limited to the specific constructions

herein described, but can be embodied in other forms without departure from its spirit.

I claim:

1. A socket plug comprising a socket engaging member and a disconnectible lead wire carrying member, and locking means on said socket engaging member actuated by the joining of said members for preventing its entry into or withdrawal from a socket while the plug is assembled.

2. A separable socket plug comprising a socket engaging member, and a lead wire carrying member, and a movable bar on said socket engaging member displaced against a socket wall when the plug is assembled therein.

3. A separable socket plug comprising a socket engaging member and a lead wire carrying member, and a spring actuated locking bar on said socket engaging member displaced against a socket wall when the plug is assembled therein.

4. A separable socket plug comprising a socket engaging member and a lead wire carrying member, means on said socket engaging member for locking said member in a socket, and means on said wire carrying member for actuating said locking means when the said members are assembled and disassembled in a socket.

5. A separable socket plug comprising a socket engaging member having a spring, a pawl on one end of said spring, and a bearing and guide plate for said pawl mounted thereon, and a lead wire carrying member having extension terminals thereon for insertion into the socket engaging member, said extension terminals serving when the plug is assembled in a socket to actuate the spring and move the pawl into locking position against the wall of the socket.

6. In a two-part socket plug for electrically connecting a pair of conductors to the center and threaded shell terminals of an electric wall socket, an insulating body member, a cap having a pair of prongs projecting into said body member, separate means in said body member for connecting said prongs with said center and shell terminals respectively, and means common to one of said separate means for locking said plug in said socket when the prongs are inserted in said body member.

In testimony whereof I hereto affix my signature.

SWEN R. SWENSON.
